(57) **CLAIM**

The ornamental design for an adapter for portable device, as shown and described.

DESCRIPTION

FIG. 1 is a top front left perspective view showing a first embodiment of my new design;

FIG. 2 is a bottom rear right perspective view of the first embodiment of my new design;

FIG. 3 is a front view of the first embodiment of my new design;

FIG. 4 is a rear view of the first embodiment of my new design;

FIG. 5 is a left side view of the first embodiment of my new design;

FIG. 6 is a right side view of the first embodiment of my new design;

FIG. 7 is a top view of the first embodiment of my new design;

FIG. 8 is a bottom view of the first embodiment of my new design;

FIG. 9 is a top front left perspective view showing a second embodiment of my new design;

FIG. 10 is a bottom front right perspective view of the second embodiment of my new design;

FIG. 11 is a bottom rear right perspective view of the second embodiment of my new design;

FIG. 12 is a front view of the second embodiment of my new design;

FIG. 13 is a rear view of the second embodiment of my new design;

FIG. 14 is a left side view of the second embodiment of my new design;

FIG. 15 is a right side view of the second embodiment of my new design;

FIG. 16 is a top view of the second embodiment of my new design;

FIG. 17 is a bottom view of the second embodiment of my new design;

FIG. 18 is a reference perspective view of the second embodiment of my new design installed on a portable electronic device;

FIG. 19 is a top front left perspective view showing a third embodiment of my new design;

FIG. 20 is a bottom front right perspective view of the third embodiment of my new design;

FIG. 21 is a bottom rear right perspective view of the third embodiment of my new design;

FIG. 22 is a front view of the third embodiment of my new design;

FIG. 23 is a rear view of the third embodiment of my new design;

FIG. 24 is a left side view of the third embodiment of my new design;

FIG. 25 is a right side view of the third embodiment of my new design;

FIG. 26 is a top view of the third embodiment of my new design; and,

FIG. 27 is a bottom view of the third embodiment of my new design.
